UNITED STATES PATENT OFFICE.

HENRY MILLER, OF PITTSBURG, PENNSYLVANIA, ASSIGNOR OF THREE-FOURTHS TO THOMAS MILLER, DANIEL H. STOEHR, AND ALVA A. MOORE, ALL OF SAME PLACE.

DESIGN FOR A DOOR-KNOB.

SPECIFICATION forming part of Design No. 19,976, dated July 1, 1890.

Application filed June 4, 1890. Serial No. 354,296. Term of patent 3½ years.

To all whom it may concern:

Be it known that I, HENRY MILLER, a citizen of the United States, residing at Pittsburgh, in the county of Allegheny and State 5 of Pennsylvania, have invented a certain Design for Door-Knobs; and I do hereby declare the following to be a full, clear, and exact description of the invention, reference being had to the accompanying drawing, which 10 forms part of this specification.

My invention has relation to designs for door-knobs; and it consists of a sphere flattened on one side and formed with a projecting collar at that side to receive the stem 15 which passes through the door and the spherical portion containing an image of a bouquet or group of flowers composed of a central flower surrounded by other flowers, each flower being provided with a bulbous, colorless, shining 20 pistil.

In the illustration accompanying this specification I have shown a door-knob consisting of a transparent sphere A, having at one side a collar a, and containing an image of a bouquet of flowers consisting of a central flower 25 B and surrounding flowers b b, each flower being provided with a bulbous, colorless, shining pistil c.

Having described my design, I claim—

The design for a door-knob herein shown 30 and described, consisting of a sphere having a collar at one side, and containing an image of a bouquet of flowers, said flowers being provided with bulbous, colorless, shining pistils.

In testimony that I claim the foregoing I 35 have hereunto set my hand this 7th day of March, 1890.

HENRY MILLER.
